UNITED STATES PATENT OFFICE.

NORBERT M. LA PORTE, OF BALTIMORE, MARYLAND, ASSIGNOR TO THE CROWN CORK AND SEAL COMPANY OF BALTIMORE CITY, OF BALTIMORE, MARYLAND, A CORPORATION OF MARYLAND.

CLOSURE-APPLYING MECHANISM.

1,080,114.

Specification of Letters Patent.

Patented Dec. 2, 1913.

Application filed February 26, 1912. Serial No. 679,810.

To all whom it may concern:

Be it known that I, NORBERT M. LA PORTE, a citizen of the United States, residing at Baltimore, State of Maryland, have invented certain new and useful Improvements in Closure-Applying Mechanism, fully described and represented in the following specification and the accompanying drawings, forming a part of the same.

This invention relates to mechanism for applying metal closures, such as the well-known crown corks, to fragile receptacles, such as bottles. Bottles and similar receptacles made of vitreous material to which metal closures such as crown corks are applied, although of the same capacity and designed to be of the same length, vary considerably in length. The machines by which such closures are applied are usually operated by mechanism, however, which is designed to produce movements of the same extent for each capping operation. Because of the varying height or length of the receptacles, it has been found necessary to employ a mechanism for controlling the pressure to be applied during the capping operation. A form of such mechanism which has been widely used commercially is illustrated in the patent to Painter, No. 638,354, dated December 5, 1899. In this mechanism each bottle is carried by what may be termed a holder which is to be moved up to force the bottle into proper relation with the capping head, this head operating to apply the closure. The movement of the holder is controlled by a release mechanism which operates to prevent further upward movement of the holder when a predetermined degree of pressure had been brought to bear upon the bottle. While said mechanism is efficient in operation it is expensive in construction.

The present invention has for its object to produce an improved mechanism for applying metal closures to bottles or similar receptacles which is simple in construction, which operates efficiently at a high rate of speed, and which embodies means for preventing breakage due to the variation in height of the receptacles.

With this and other objects not specifically referred to in view, the invention consists in certain constructions, and in certain parts, improvements and combinations as

will be hereinafter fully described and then 55 specifically pointed out.

Referring to the accompanying drawings: Figure 1 is a sectional elevation of so much of a closure applying mechanism embodying the invention as is necessary to an 60 understanding thereof, and Fig. 2 is a sectional elevation showing a modified construction embodying the invention.

Machines constructed in accordance with the invention will be provided with closure 65 applying means, the particular construction of which may be varied. In the machine illustrated, such closure applying means is generally indicated at 10 and comprises a plurality of cap applying dies carried in a 70 frame 20 which is supported by a sleeve 21, this sleeve surrounding a vertical post 12. The particular construction of closure applying mechanism referred to is fully shown and described in patent to Painter, No. 75 628,354, Dec. 5, 1899, hereinbefore referred to, and therefore further specific description of such means is unnecessary, as reference to that patent may be had for the same.

Constructions embodying the invention 80 will also include a receptacle holder, and constructions which embody the invention in what is regarded as the best form will include a plurality of such holders. While the construction of these holders may be 85 varied, as illustrated they comprise cylinders 13 provided with the usual centering flanges indicated at 23. The means for supporting and operating the holders may be varied and will be varied in accordance with 90 the particular construction of holder employed. As illustrated, there is provided a carrier or turret 11 which rotates about the vertical standard 12, the holders 13 being located in sockets 14 formed in the turret. The sockets and holders are so located as to be in vertical alinement with the closure applying devices, each holder 13 having associated therewith an individual closure applying device. The sleeve 21 is 100 bolted to the turret at 22, so that the closure applying devices rotate with the turret and holders. The turret may be rotated from a power shaft 15 carrying at its inner end a bevel gear 16 meshing with a toothed 105 ring 17, the ring being attached to a flange 18 which is carried on a sleeve 19 forming a part of the turret construction.

Constructions embodying the invention will include an actuator for causing a relative movement between the closure applying devices and the holders during the closure applying operations. While the particular construction and arrangement of this actuator may be varied and will vary according to the character of the movement which is to be produced, in the particular construction illustrated, the actuator comprises a cam 29 which provides a circular track around which the holders are carried by the movement of the turret, the holders being provided with anti-friction wheels 30. With this construction, as the turret rotates, the holders will be given a rising and falling movement, each holder as it runs up on the high part of the cam being carried upward toward the closure applying device with which it co-operates. During the operation of the mechanism, therefore, each bottle or other receptacle carried by a holder will be moved into operative relation with the closure applying device co-operating with that holder.

Constructions embodying the invention will further include a controller which operates upon the actuator and which determines the amount of pressure to which any receptacle may be subjected during the capping operation, so that breakage, due to variation in height of the receptacles, may be avoided. The construction of this controller may vary and will vary in accordance with the particular form of actuator employed, two constructions of controller being shown.

Referring more particularly to Fig. 1, the cam 29 before referred to is pivoted at 35 to an ear on the frame, and there is provided a lever 32 pivoted to the frame at 33, the lever being provided with an upward projection as 34 which bears on the under side of the cam underneath the high point thereof. The lever is provided with a weight, as 31, which may be made adjustable along the lever by a set screw 31' to determine the amount of upward pressure on the cam produced by the weight. It is obvious that with this construction the upward thrust and consequent movement of each of the holders 13 will be limited by the action of the weight, so that only a predetermined amount of pressure, viz., that produced by the weight in a given position, can be applied to any receptacle. The construction will be so proportioned that the cam will produce an upward movement of each holder and a consequent predetermined pressure by the closure applying device sufficient to cause a closure to be applied to the shortest receptacle without disturbing the weight. If, however, a longer receptacle is present on any holder, when an upward movement of the receptacle has been produced which is sufficient to cause the pre-

determined pressure to be exerted on the closure which is being applied to the receptacle, the inner end of the lever 32 will be depressed and breakage of the receptacle prevented. A limiting stop, as 27, may be employed to positively determine the extent of upward movement of each of the cylinders 13, and the cylinders may be turned off to provide shoulders 25 which co-operate with the shoulders 26 on the sockets 14, thus determining the amount of downward movement of the holders.

In the construction illustrated in Fig. 2, the controller comprises a plunger 36 located under the high point of the cam, this plunger being located in the cylinder 37. The cylinder is provided with an opening 38 through which fluid may be forced into and out of the cylinder, accordingly as the cam is subjected to pressure above or below the predetermined pressure. The cylinder 37 is supported by a bracket (not shown) attached to the frame that supports the table 28. A pressure reservoir, as 39 is employed, this being connected with the cylinder 37 by means of a pipe 40. The reservoir is provided with a piston, as 41, gas or air under pressure being introduced into the reservoir above the piston by means of a pipe 42 controlled by a cock 43. Pressure produced on the piston 36 by the cam 29 will tend to cause the fluid in the cylinder 37 to be forced through the pipe 40 into the reservoir 39, and when this pressure is sufficient to overcome the pressure of the gas or air on the piston 41, the piston 36 will be depressed, thus preventing the cam from producing a further upward movement of any holder 13. A controller cock, as 44, may be employed in connection with the pipe 40. The frame of the machine may be provided with a table as 28 in which the turret rotates.

Changes and variations may be made in the constructions by which the invention claimed is carried into effect. The invention claimed, therefore, is not to be confined to the particular constructions herein described and illustrated in the accompanying drawings.

What is claimed is:—

1. In a machine for applying metal closures to fragile receptacles, and in combination, a plurality of holders, a plurality of closure applying devices corresponding in number with the holders, an actuator adapted to produce a relative movement between each holder and its corresponding closure applying device, and a controller operating upon the actuator whereby the amount of relative movement and the consequent pressure on the receptacle is determined.

2. In a machine for applying metal closures to fragile receptacles, and in combination, a plurality of holders, a plurality of

closure applying devices corresponding in number with the holders, an actuator adapted to successively move each holder toward its coöperating closure applying device, and 5 a controller operating upon the actuator, said controller governing the actuator and holder, and thus determining the amount of pressure exerted in the closure applying operation.

10 3. In a machine for applying metal closures to fragile receptacles, and in combination, a rotating carrier, a plurality of holders mounted therein, a plurality of closure applying devices corresponding in number 15 with the holders and rotating with the carrier, an actuator for effecting a relative movement between each holder and its coöperating closure applying device, and a controller operating upon the actuator 20 whereby the amount of relative movement and the consequent pressure on the receptacle is determined.

4. In a machine for applying metal closures to fragile receptacles, and in combination, 25 a rotating carrier, a plurality of holders mounted therein, a plurality of closure applying devices corresponding in number with the holders and rotating with the car-

rier, a movable actuator for causing each holder in succession to approach and recede from its coöperating applying device, and a controller governing the actuator and each holder, and thus determining the amount of pressure exerted in the closure applying operation.

5. In a machine for applying metal closures to fragile receptacles, and in combination, a rotating carrier, a plurality of holders mounted therein, a plurality of closure applying devices corresponding in number 40 with the holders and rotating with the carrier, a movable actuator cam for causing the holders in succession to approach and recede from their coöperating closure applying devices, and a controller operating on the cam 45 for governing the amount of movement of the actuator cam and the holders and thus determining the amount of pressure exerted in the closure applying operation.

In testimony whereof, I have hereunto set 50 my hand in the presence of two subscribing witnesses.

NORBERT M. LA PORTE.
